UNITED STATES PATENT OFFICE.

EDWARD A. EVERETT, OF NEW YORK, N. Y.

SIGHTING DEVICE.

Application filed January 18, 1928. Serial No. 82,156.

This invention relates to sighting devices for accurately determining the location of an object and is illustrated in application to railway signals of the light type wherein the beam of light from the signal is projected in a predetermined direction and the source of illumination is located with relation to the focal point of a lens. The invention comprises a detachable sighting device for the 10 housing of the signal by means of which the signal may be adjusted to project the beam of light in a predetermined direction, also, it comprises a novel type of sighting tube which is particularly adapted for sighting 15 an illuminated object at close range. These and other objects of the invention will be more particularly understood from the following specification and the accompanying drawings, in which, Fig. 1 is a sectional elevation of a signal lamp embodying my invention, Fig. 2 is a plan view from the top of the lamp shown in Fig. 1, Fig. 3 is a sectional elevation looking from the rear end towards the lens, Fig. 4 is a sighting tube in 20 section constructed according to my invention and Fig. 5 is an end view of the sighting tube at the end opposite the eye piece.

In the art of railway signaling the use of electric lights for illuminating the signal indication has become quite general. These lights are obtained from low voltage bulbs which are energized from a primary or storage battery and in order to economize on the battery consumption the illumination is 30 limited. In order to obtain the maximum results from the light under these conditions it is necessary that the source of light be positioned accurately at the focal centre of the lens and that the beam of light from the 35 signal be properly directed along the track. These results are obtained in the present disclosure in a simple and practical manner.

Referring to the drawings, 11 is the housing of the signal device which is made of a 40 unitary casting with an aperture in the top covered by the circular cover 12 which is clamped in place by the bar 16 pivoted at 17, secured to the cover at 18 and clamped by the wing nut 19 on the eye bolt 38 through the 45 jaws 39 of bar 16. This construction is substantially the same as my co-pending application Serial No. 60,899, filed Oct. 6, 1925.

The base of the housing is adjustably supported through a socket 13 by a bracket arm 50 such as shown in the co-pending application

referred to. The lens 14 is secured in a turned recess in the casting and held in place by the lens ring 15.

The signal is illustrated by the lamp bulb 21 through the concentrated filament 22. 60 This bulb is supported by a base 23 secured to a plate 24 which is adjustably positioned by the adjusting screws 25. This adjustable support for the lamp bulb is similar to that shown in U. S. Patent 1,535,218, issued in 65 my name on April 28, 1925, and further description is not deemed necessary in this case except to note that the filament of the lamp bulb is adjustable in all directions with reference to the axis of the lens 14. The 70 conductors for the circuit of the lamp bulb are led through a block of insulation 29 and the terminals are accessible through the detachable cover 30.

The rear wall of the housing 11 is provided with a cast boss 27 which is drilled at 75 28 to form a sighting tube and to which the reflector 26 is screwed or attached at the inner end. Another boss is cast in this wall at 31 and is drilled to receive a tube or stem 32 80 and is threaded at the outer end to receive a cap or cover.

The stem 32 is a snug fit in 31 and carries the arm 33 with the head 34 which clamps the sighting tube 35 having the eye piece 36. 85 It is apparent that the arm 33 is rotatable upon the stem 32 as a centre and may swing in an arc across the top of the housing. This device is detachable, being inserted in aperture 31 for use and when removed, this aperture is closed by a cap.

In Fig. 3 another sighting device 41 is 90 shown which is accessible when the cover 12 is removed, the support of this device is cast integral with the housing.

A novel type of sighting tube as shown in Figs. 4 and 5 is used in practicing my invention. This has a tubular body 35 to which the eye piece 43 is secured and which clamps the cup shaped member 45 in place. This 100 member has a small central aperture at 46 in line with the aperture 44 in the eye piece. The opposite end of the sighting tube is closed by a glass disc 42 which may be secured by spinning over the end of the tube, 105 by a ring or by other means well understood in this art. This disc is provided with a series of concentric rings as at 47 by means of which the sight is located.

In surveying instruments it is common 110

practice to locate the sight by means of cross hairs. Cross hairs have not proved satisfactory when taking a sight of a source of illumination such as is necessary in the 5 present case for sighting the filament of the bulb when it is lighted at night. It has been found in practice that the cross hairs which are made of fine lines are entirely obliterated by the source of light, especially 10 when the light is close to the sighting tube. When the cross-hairs are widened to avoid this condition the point of cross is enlarged and intercepts the sight on the filament and may entirely obscure the filament. By the 15 arrangement of concentric rings in the end of the sighting tube an accurate sight on the filament can be taken when it is illuminated. The sight through the eye piece covers the spread between the lines *g*, the 20 stand of the bulb is then adjusted until the filament is brought within the circles and until, eventually, it is brought into the centre of the disc. These rings may be made of lines of different widths as indicated with 25 the thicker lines preferably towards the centre. The rings enable the eye to readily determine the direction of adjustment required and to determine when the centre has been reached. It should be noted that 30 the rings are easily applied to the disc when the tube is set up in a lathe by bringing a diamond cutter into contact with the glass.

In this construction it will be observed that the tube 28 drilled in the housing at 35 27 is in line with the axial centre of the lens 14, the recess for the lens and the drill for 27 being jigged to secure this result. The boss 13 for the pivot of the supporting bracket is also drilled with relation to the 40 axial centre of the lens to be perpendicular to and intercept this centre.

The axial centre of the lens is indicated by the line *a—a* passing through the centre of tube 28. A sight can be taken on this 45 line from the outside of the housing. The boss 31 in the housing is drilled parallel to 28 so that the line *b—b* is parallel to line *a—a* and the arm 33 and head 34 hold the sighting tube 35 with its axis *c—c* parallel 50 to *b—b*. It will thus be observed that while the sighting tube 35 is pivotably rotatable about the stem 32 it is always maintained parallel with the line *a—a* and with the axial centre of the lens. The tube 35 is 55 used for aligning the lamp housing so that the beam of light projected on the track will be in a predetermined direction. This tube is rotatable on stem 32 to clear local objects as for instance a semaphore spectacle that 60 may be located in front of the lens 14. The vertical support of the signal is pivoted on line *d—d* which intersects the line *a—a* and the filament 22 so that the device may be rotated on this support without changing

the relation of the lens, the filament and the 65 bracket.

The sighting tube 28 is constructed similar to tube 35 with the end disc having concentric rings which enables the filament, which is close to the end of the tube to be 70 properly sighted when adjusting the lamp support.

In order to determine the exact position of the filament back from the lens the 75 sighting tube 41 is provided sighting the filament on line *e—e* at right angles to line *a—a*. This sighting device is enclosed by the cover 12.

Having thus described my invention, I 80 claim:

1. In a sighting device for a light projector, the combination, a housing with a projecting lens, a source of illumination in said housing, a sighting device in the wall of said housing for locating said source in 85 the axis of said lens, an arm supporting a sighting tube for aligning said projector, a stem carrying said arm and a receptacle in the wall of said housing off-set from the axis of said lens for detachably supporting 90 said stem.

2. In a sighting device for a light projector, the combination, a housing with a projecting lens, a source of illumination in said housing, a sighting device in the wall 95 of said housing for locating said source on the axis of said lens, a second sighting device at right angles to said axis for locating said source at the focus of said lens, an arm supporting a sighting tube for aligning said projector, a stem carrying said arm and a receptacle in the wall of said housing off-set 100 from the axis of said lens for detachably supporting said stem.

3. In a system for sighting a source of 105 illumination, the combination of a tube closed at one end with a non-transparent disc having a sight hole in the centre thereof and closed at the opposite end with a disc of glass, said glass disc having a circle 110 of comparatively broad lines inscribed about the centre thereof and located comparatively close to the source of illumination.

4. In a system for sighting a source of 115 illumination, the combination of a tube closed at one end with a non-transparent disc having a sight hole in the centre thereof and closed at the opposite end with a disc of glass, said glass disc having a plurality of circles, the innermost of which is formed of comparatively broad lines inscribed about the centre thereof and placed comparatively close to the source of illumination.

In testimony whereof I have affixed my 125 signature.

EDWARD A. EVERETT.
